UNITED STATES PATENT OFFICE.

CHARLES CLINTON MOORE, OF COLUMBUS, OHIO.

HANGING GUTTER.

SPECIFICATION forming part of Letters Patent No. 498,286, dated May 30, 1893.

Application filed November 28, 1892. Serial No. 453,430. (No model.)

To all whom it may concern:

Be it known that I, CHARLES CLINTON MOORE, a citizen of the United States, residing at Columbus, in the county of Franklin 5 and State of Ohio, have invented a certain new and useful Improvement in Eaves-Troughs or Hanging Gutters, of which the following is a specification.

My invention relates to the improvement 10 of eaves troughs or hanging gutters for buildings and the objects of my invention are, to provide a simple, reliable and effective means of coupling the joints or sections of an eaves trough; to obviate the necessity of employing 15 solder in said connection; to so construct my improved trough as to admit of its sections being rapidly and securely coupled in any desired lengths and to produce other improvements which will be more specifically 20 pointed out hereinafter. These objects I accomplish in the manner illustrated in the accompanying drawings, in which—

Figure 1 is a view in perspective of two sections of eaves trough showing the same 25 united by my improved coupling. Fig. 2 is a central longitudinal section of portions of two united joints. Fig. 3 is a transverse section on line xx of Fig. 4 and Fig. 4 is a bottom view of the jointed sections of two sections.

Similar letters refer to similar parts throughout the several views.

a and a' represent respectively, joints or sections or portions of joints or sections of my 35 improved gutter, each of said joints being formed of suitable sheet metal and having the usual concaved or gutter shape. As shown in the drawings, the upper longitudinal edges of these sections are bent outward and thence 40 upward to form substantially L-shaped flanges b , the vertical or upwardly projecting portions of these flanges being doubled, as shown at b' . In this manner substantially hook shaped edges are formed which will admit of 45 the edges of one section being engaged with the edges of another.

In the formation of each of the gutter sections above mentioned, I extend the concaved or gutter portion at one end thereof. This 50 extended portion which is indicated at c is as

shown at c' , folded or bent backward upon the under convex surface of the gutter joint body, the portion thus folded being again bent or folded forward, upon itself, as indicated at d in Fig. 2. This last fold d is made 55 at such point in the extension c as to cause the outer fold leaf d' produced thereby to extend forwardly beyond the first fold c' . In forming the last fold d , I cause the outer leaf d' thereof to extend parallel with the leaf of 60 the first fold c' and at a short distance from the latter. At the folding point d , I also produce a slight outward bend of the material so folded, resulting as shown in the formation when viewed from the exterior of the 65 joint in a bead or struck-up portion d^2 , while the leaf d' is at its outer or forward end also bent outward and thence inward to form a correspondingly shaped lip bead d^3 .

As shown in the drawings, the fold extension-portion c of the gutter joint is bent to 70 conform to the outline of the convex portion of the gutter, the inner fold leaf produced by the fold c' being pressed closely into engagement with the outer surface of the gutter section. As shown more plainly in Fig. 2 of the 75 drawings, I provide the opposite end of the gutter section or joint, from that above described, with a slightly out-turned or sprung edge. (Indicated at e .)

In connecting two of the gutter sections above described, I insert the sprung end portion e of one section beneath the bead-shaped lip d^3 of the fold d' and within the socket between said leaf d' and the inner leaf of the 85 extension c of the adjoining section. The insertion being complete, it will be seen that the flaring or sprung end e of the section will spring outward into the seat formed at the end of said socket by the out-turned or 90 beaded projection d^2 , said seat thus serving to form a shoulder with which said flaring end e may engage. It is evident that during the insertion of one section within the socket of the other as above described, the out-turned end portion e may by contact with the fold leaf d' press the latter slightly outward and that when said out-turned end e has reached its inner seat as above described, said fold leaf d' will readily spring into its 95 100

place against the surface of the inserted portion of the section, thus forming a close connection between the two sections or joints.

f represents a transverse hanger or cross-bar which extends between the sides of the gutter immediately over the joining point of two sections. This bar hanger rests at opposite points upon the bases or horizontal portions of the flanges *b* and has its end portions 10 bent or shaped to fit or fold about said flange portions *b*, as shown. The ends of this bar *f* are as shown in Fig. 4 of the drawings, made pointed said pointed ends being as shown in Fig. 3 of the drawings, forced into the material forming one of the jointed sections, as shown at *g*. It will thus be seen that the hanger bars will not only provide means for suspending the gutter, but that said bars will 15 serve as cross-braces at the joints of said gutter and assist in the operation of retaining the sections in close connection.

From the construction herein shown and described, it will be seen that means are provided for establishing a connection between 20 the joints or sections of eaves trough which obviates the necessity of employing solder or other similar substance to produce said connection. It will also be seen that the herein described construction is such as to render 25 the gutter or trough completely water-tight at the joints and admit of said joints being readily and easily produced.

Owing to the character of the connection herein shown, it is evident that I may produce the gutter sections in any desired lengths 30

and that if desired, the trough may be readily unjointed or taken apart without injury to the sections thereof.

It will be observed that the method of connection which I employ is such as to obviate 40 the necessity of the use of what are termed ordinarily right and left hand joints, that is each alternate joint of a length of gutter formed to fit within or connect with the intervening joints. It will thus be observed that 45 the joints of my improved device are interchangeable being of the same construction and one joint to be adapted to be connected with the other.

Having now fully described my invention, 50 what I claim, and desire to secure by Letters Patent, is—

In an eaves trough for hanging gutters, the combination of the trough sections *a*, an extension *c* on one end of each of said sections, said extended portion being folded 55 backward upon the body of said section and refolded to form a curved socket having as described an off-set at its inner end produced by the formation of the bead *d*, the opposite 60 end of each of said gutter sections having an outward bend, or flare *e*, the socket of one section adapted to receive as described, the flaring end of another, substantially as and for the purpose specified.

CHARLES CLINTON MOORE.

In presence of—
BARTON GRIFFITH,
C. E. HOLDSWORTH.
